Continuation-in-part of abandoned design application Ser. No. 357,230, May 4, 1973. This application Oct. 3, 1974, Ser. No. 511,744

Term of patent 14 years

Int. Cl. D12—05

U.S. Cl. D13—7 R

FIG. 1 is a perspective view of a pair of balustrades for passenger conveyors showing our new design.

FIG. 2 is a side elevational view of FIG. 1.

FIG. 3 is a front elevational view of FIG. 1.

FIG. 4 is a perspective view of a second embodiment of the design of FIG. 1.

FIG. 5 is a side elevational view of FIG. 4.

FIG. 6 is a front elevational view of FIG. 4.

The broken line showing of a connecting means in FIGS. 1, 3, 4, and 6 is for illustrative purposes only and does not form a part of the claimed design.

This is a continuation-in-part of design application Ser. No. 357,230, filed May 4, 1973, abandoned.

We claim:

The ornamental design for a pair of balustrades for passenger conveyors, as shown and described.
